MOVEMENT FOR OPERATING SIGNS, ADVERTISING DEVICES, AND THE LIKE

Arthur Samuel Waddington, Dartford, England,
assignor to International Novelty Company,
Limited, London, EnglandApplication January 12, 1938, Serial No. 184,657
In Great Britain August 20, 1937

6 Claims. (Cl. 40—51)

This invention relates to a new or improved movement for operating signs, advertising devices and the like, a part or the whole of which is required to move.

5 The principal object of the invention is to provide a movement which will be simple and so cheap to manufacture that signs and advertising devices having movable parts will be more widely used than has, on account of expense, been the case hitherto.

According to the present invention, the movement consists of a member which is mounted at its end on coaxial pivots so that the member can oscillate as a pendulum about the pivots, and to 15 effect oscillatory movement of this member it is provided with one part of an electromagnet the other part of which is carried by a fixed support carrying also the pivots and the electric magnet is energized by a battery which is carried by and 20 coacts with a member in producing the pendulum action; in addition there is provided a switch mechanism for controlling the circuit of the battery for energizing the electromagnet and this switch mechanism has a part adapted for operation 25 by the member or by some part associated with or moved by it.

The invention is illustrated in one form of construction in the accompanying drawings in which Figure 1 is a front elevation; Figure 2 a 30 vertical section and Figures 3 and 4 detail views to a larger scale and at right angles to one another of a movement in accordance with the invention and Figures 5 and 6 are respectively front elevation and end elevation showing a typical sign to 35 which the movement shown in Figures 1-4 can be applied.

Referring to the drawings, 1 is a strip of electrically insulating material preferably wood, which is carried at its upper end from pivots on a support 2. The pivots consist of a bar 3 secured in 40 the support 2 and coned at its ends as at 4 to receive cupped pivot screws 5 screwed in opposed limbs of a U-shaped metal bracket 6 secured by one of its limbs to a face of the strip 1 near or at 45 its upper end, the limbs of the bracket 6 straddling the conically ended bar 3; the support bracket 2 is formed of a length of wood or other electrically insulating material.

The strip 1 is provided with two metal clips 7, 50 8; the clip 7 is provided to secure to the strip at its lower end the coil 9 of an electro-magnet while the other clip 8, which is secured between the ends of the strip is arranged to enable a single-cell dry battery 10 to be sprung into it. 55 To connect the coil 9 in circuit with the battery 10,

one end (shown at 11) of the coil 9 is connected to the metal clip and this clip in turn is engaged by the base of the usual metal container of the battery 10, this container forming as is usual one pole of the battery. The other end of the coil 9 5 is connected by a wire 12 to a pin 13 secured at the upper end of the strip 1 above its conical pivots and this pin forms one part of a switch, hereinafter referred to. The other part of the switch is connected to the conical pivots 4 and 10 hence to the U-shaped bracket 6 and the base of this bracket is engaged by the usual top cap 14 of the battery 10 (forming the other pole of the battery). To ensure the base and the top of the battery 10 making firm contact with the coil clip 15 17 and with the U-shaped bracket 6, the coil clip 17 is arranged to be somewhat springy so that when the battery is clipped in position in the clip 8 the coil clip 17 is slightly bent so as to react to 20 make firm contact itself with the base of the battery 10 and to urge the top cap 14 of the battery 10 into firm contact with the U-shaped bracket 6.

The other part of the electromagnet is constituted by an armature consisting of a permanent magnet formed by a cylindrical rod 16 and this rod is secured to a casing 17 to which the support 2 is also secured. The rod as shown is secured at one end only to the casing and projects at its free end into the aperture of the coil 9 30 30 or to enable the rod to be supported at both ends, the rod may be of composite form, one end being of iron and the other of brass or other non-magnetic material and the two ends screwed to brackets secured to the casing. 35

With the parts so far described it will be seen that if the switch referred to is closed and opened in step with oscillation of the strip 1 about the conically ended pivot bar 3 the strip will be caused to oscillate by the co-operation between the coil 9 and the armature 16. It will be observed that because the strip 1 carries not only the coil 9 but also the battery 10, the resulting total weight of the strip 1 and the parts carried by it will enable the assembly to operate as a 40 45 pendulum: this enables the oscillation of the strip 1 when once it has been started to be maintained with comparatively little effort and in any case well within the supply capacity of a small standard battery such as that shown. Because the power drawn from this battery is small it will have 50 a comparatively long life and so the cost of maintenance of the device is low.

The desired operation of the switch referred to is effected by utilizing the oscillation of the strip 55

so as to actuate it in such a manner that the switch is closed when the strip 1 swings in one direction and opened when it swings in the other direction.

5 The pin 13 already referred to as forming one part of the switch enters with clearance a slot 18 formed between two finger-like parts 19, 20 both secured to a spindle 21 supported in a metal bracket 22 secured to the fixed support 2, the spindle 21 being electrically connected to the pivot bar 3 and hence (as already described) to one pole of the battery 10 the other pole being connected to the coil 9. One of the finger-like parts 19 is formed of metal and so by its connection to the spindle 21 is connected in circuit with the battery while the other finger 20 is of electrically insulating material such as fibre. Thus, when the strip 1 is swung in one direction, the pin 13 takes up its clearance in the slot 18 and engages say the metal finger 19 forming one wall of the slot 18 and so closes the circuit causing the energization of the coil 9. When the strip 1 swings in the other direction the pin 13 takes up its clearance in the other direction 25 and so leaves the metallic finger 19 thereby opening the energizing circuit of the coil 9 and moves into engagement with the fibre finger 18 so maintaining an open circuit. The action of making and breaking the circuit of the coil causes the strip 1 to oscillate.

30 The connection between the spindle 21 and the U-shaped bracket 6 is effected through a short length of wire 23 connected at one end to the pivot bar 3 and at the other end secured to a nail or screw 24 constituting a binding post to which can be connected one end of a coil spring 25 the other end of which is looped and passed over the spindle 21. This arrangement enables the connections very expeditiously to be changed over to include a second and larger battery external of the strip by arranging on the fixed support 2 connections for attachment to the terminals of the other battery, one connection being coiled around the pivot bar 3 and the other passed through and allowed to project above the fixed support 2 to constitute a second binding post to which the spring 25 can be attached as an alternative to the first binding post.

55 By the pivotal support described for the strip 1, it is possible to tilt the mechanism from the vertical to an appreciable extent without affecting the ability of the strip to swing, this feature being of importance in some applications where it is desirable to arrange the mechanism in a tilted position.

60 The invention is concerned with the foregoing mechanism rather than with the particular use to which the oscillations of the strip 1 are put. It will be apparent that there are many such uses; for example the strip 1 may (as is shown in the drawings) have a block 26 attached to it co-axially with the conical pivots 4 this block projecting through an aperture 27 in the casing 17: this block can be provided with two pins 28 65 to enter apertures in a block 29 to which the device to be moved is secured, the whole providing a readily detachable connection between the movement in the casing 17 and the device to be operated by this movement.

70 In the arrangement shown the movement is utilized to rock a cardboard cut out 30 of a human face, this cut out being secured to the block 29. The housing which can be made of cardboard in the form of an open box is secured to the back 75 of a cut out stand or easel structure 31 and the

housing can be closed by a lid 32 fitted after the housing is secured to the stand or easel 31, the lid being removable to gain access to the movement inside the housing 11. Any desired advertising or announcement matter could of course 5 be applied to one or both cut outs the whole forming a device to which attention will be drawn by the moving part. It will be appreciated that other uses may be made of the oscillatory movement of the strip 1: for example the strip 1 could have an arm secured to it and the arm have a pin which carries at its outer end a sign, flag, or other device movable over a fixed card bearing a sign or other device, the sign on the arm thus having an oscillatory movement which 10 could be used to direct attention to that on the card. Again one of the cupped pivot blocks could be extended to impart angular movement to an arm from which motions are taken by various parts of a device. Moreover, by employing two 15 signs, one connected to some moving part of the mechanism direct and the other connected through a reversing link or lever system, the two signs can have movements imparted to them in opposite senses. A combination and/or multiplication of these features could be employed. 20

25 It will be seen that these movements possess the advantages that in addition to costing little to maintain, they can be produced as units cheaply and in large quantities and readily applied as 30 required to various devices and signs. The movement will thus enable moving signs to be employed without the deterrent of large initial cost and comparatively high maintenance costs and so will enable such signs to be extensively employed at small cost by firms desirous of distributing signs to advertise their goods.

35 The mechanism described could be made as a self-contained unit arranged to be inserted in different casings designed for various uses or different forms of sign.

40 What I claim is:—

1. In a sign having a moving portion, a mechanism for effecting movement of the said portion and comprising a movable part, means supporting 45 the said part for pivotal oscillatory movement, an electro-magnetic device effecting oscillatory movement of the said movable part, an energizing battery for the said electromagnetic device, means securing the battery to the said movable part so that the weight of the battery assists the 50 movable part to function as a pendulum, a switch mechanism controlling the circuit of the electro-magnetic device, means operating the switch mechanism from the movable part whereby movement of this latter part opens and closes the switch, and connections from the said movable part to the moving portion of the sign.

55 2. In a sign having a moving portion, a mechanism for effecting movement of the said portion and comprising a movable part, means supporting 60 the said part for pivotal oscillatory movement, an electro-magnetic device including a magnet and a coil, means securing the coil to the movable part, an energizing battery for the coil, means 65 securing the battery to the movable part so that the weight on the battery will coact with the movable member to enable the latter to function as a pendulum, a switch mechanism controlling the circuit of the battery and coil, means operating 70 the switch mechanism from the movable part whereby movement of the part opens and closes the said circuit to cause the movable part in combination with the weight of the said battery to oscillate as a pendulum, and connections from the 75

said movable part to the moving portion of the sign.

3. In a sign having a moving portion, a mechanism for effecting movement of the said portion and comprising a movable part, means supporting the said part for pivotal oscillatory movement, an electro-magnetic device effecting oscillatory movement of the said movable part, an energizing battery for the said electromagnetic device means securing the battery to the said movable part so that the weight of the battery assists the movable part to function as a pendulum, a switch mechanism controlling the circuit of the electro-magnetic device, the said switch mechanism comprising a jaw member, a pin extending with clearance into the jaw member, means connecting only one side of the jaw member in circuit with the one side of the battery and electro-magnetic device, means connecting the pin in circuit with the other side of the battery and electromagnetic device, means connected to the movable part and operating to cause the jaw member and pin to have relative movement first in one direction and then in the other, whereby the switch is opened and closed, and connections from the said movable part to the moving portion of the sign.

4. A movement as claimed in claim 3 and in which the pin is carried by the movable part and

the jaw member is mounted to rock about a center external of the member.

5. In a sign having a moving portion, a mechanism for effecting movement of said portion and comprising a movable part, a bracket on said part, a bearing member straddled by the said bracket and engaged thereby to support the movable member for oscillatory movement about the bearing member, an electromagnetic device for effecting oscillatory movement of the said movable part, 10 the said device including a coil, a magnet and a battery, a clip securing the battery to the movable part with one pole of the battery in contact with the bracket, the weight of said battery co-acting with said movable member to enable the 15 latter to function as a pendulum, a second clip securing the coil to the movable part, the said second clip engaging the other pole of the battery and connecting it to one side of the coil, a switch, means connecting the other side of the 20 coil to one side of the switch, means connecting the bracket to the other side of the switch, and means to open and close the switch by movement of the movable part.

6. A movement as claimed in claim 5, and in 25 which the bearing member is provided at each end with one part of a conical bearing and the other part of which is carried by the bracket.

ARTHUR SAMUEL WADDINGTON.
